UNITED STATES PATENT OFFICE.

WILLIAM G. KENYON, OF WAKEFIELD, RHODE ISLAND.

IMPROVEMENT IN MOWING-MACHINES.

Specification forming part of Letters Patent No. 124,440, dated March 12, 1872.

SPECIFICATION.

To all whom it may concern:

Be it known that I, WILLIAM G. KENYON, of Wakefield, in the county of Washington and State of Rhode Island, have invented certain Improvements in Mowing-Machines, of which the following is a specification :

Nature and Objects of the Invention.

This invention consists in certain improvements upon a mowing-machine for which a patent was granted to me October 12, 1869; and relates to the mode of constructing the frame, raising and holding the cutting-apparatus, and in the parts that hold the knives.

Description of Drawing.

Figure 1 is a top view of the machine with the covering of the gearing removed to show the arrangement. Fig. 2 is a vertical section, taken through in direction of line *x*, Fig. 1. Fig. 3 is a vertical cross-section of part of the gearing, taken through line *y*, Fig. 2. Fig. 4 is a bottom view of the frame *A*. Fig. 5 is a cross-section of the finger-bar, &c.

General Description.

C *C* are two driving-wheels, turning loosely upon the axle *e*, but provided with ratchet-wheels and pawls in their hubs to drive the axle when moved forward. *A* is a frame, cast in one piece with the box *j* for the gearing, and the bearings *c c* for the back part of the shoe to turn in; it is connected to the axle by a sleeve, *a*, through which the axle passes, and by bearings in the side of the box *j*. *B* is an upper frame, having a bearing at one side on the sleeve *a*, and on the side of the box *j* on the other side. It holds the seat, the devices for raising the cutting-apparatus, and also has the pole *w*, to which the horses are attached, fastened to it. The gear-wheel *b* is loose on the axle *q* and meshes into a pinion, *l*, on the side of the wheel *m*, which gears into a pinion underneath it fast on the shaft to which the crank-plate *n* is attached. Gears *m l* are fastened together, and turn on a stud, *p*, which has a passage leading from a hole on its top outside of the case to the side of the stud in the middle of the bearing of the gear-wheels, for

the purpose of conveying oil directly to that spot. The crank-plate *n* and its pinion are fastened to a shaft that turns in the step *h*, which is also furnished with a passage through from the outside for oiling. *D* is a pipe or barrel, forming part of the shoe that holds the finger-bar, and turns in the bearings *c c*. A plate, *f*, is placed on a stud fastened to the frame *B*, the edge of which is grooved to receive the lifting-chain *r*, one end of which is fast to the finger-bar and the other to the top of the plate. A segment-ratchet is made in the plate, and a double pawl is put in a bearing on the frame. The short shaft to which the pawl is fastened, has on its other end a small lever, *i*, to enable the driver to operate the pawl with the toe of his boot. A spring-catch, *q*, is fastened to the frame *A*, to catch the finger-bar when raised, and a chain is carried up from the spring to the frame above to control its action. The finger-bar is cast with the guard-fingers on it, all in one piece, as shown in Fig. 5. The knives are fastened on the under side of the bar that holds them, and have the ledger-blades placed above them, as in my patent of March 28, 1871. The cap *k* is placed over the knife-bar, and has the pivots of the ledger-blades in its front edge.

The mode of operating the knives is the same as in my patent of October 12, 1869. Gear-wheel *b* has a part of a clutch on its side into which the other part of the clutch *d* which slides on the axle catches. A strip, *v*, is attached to the clutch, and has a cam in a notch at its other end furnished with a lever, *s*, to turn it, the cam being pivoted to a standard on the frame *A*. When the driver wishes to raise the cutter-bar, he catches hold of the lever *o* and draws it toward him, until the bar is upright and catches in the spring *q*, or by pushing his toe under the lever *i* the pawl is made to catch in the ratchet and hold the bar at whatever height he wishes, and when clear up the bar will catch in the spring-catch *q*, and the lever will be held up by the pawl catching under a pin on the hub. When he wishes to drop the bar, he puts his toe under the lever *i* and raises the pawl out from the pin, and by means of the lever *o* lets the bar down, the chain controlling the spring-catch so that the bar will drop out of the notch when down. The

lever that throws the clutch *d* in gear, can also be operated by the driver without leaving his seat. Everything that is necessary to be done in operating the machine, as throwing in and out of gear, raising and lowering the finger-bar, oiling, &c., can be performed by the driver without leaving his seat or letting go the reins.

What I claim as my invention is—

1. I claim the combination of the spring-catch *q* attached to the lower frame *A* and flexibly connected to frame *B*, with the finger-bar, the plate *f*, the double pawl, and toe-lever

i, all being arranged and connected substantially as described, so that the finger-bar will release itself from the catch when let down.

2. I claim the combination of the knife-bar having the knives on its under side, with the cap covering the bar, and the ledger-blades having their rear pivots in the front of the cap, substantially as and for the purpose set forth.

WM. G. KENYON.
